UNITED STATES PATENT OFFICE.

DAVID J. SEAMAN, OF SOUTH BEND, INDIANA.

DESIGN FOR FABRIC.

SPECIFICATION forming part of Design No. 34,554, dated May 21, 1901.

Application filed April 29, 1901. Serial No. 58,089. Term of patent 14 years.

To all whom it may concern:

Be it known that I, DAVID J. SEAMAN, a citizen of the United States of America, residing at South Bend, in the county of St. Joseph and State of Indiana, have invented and produced a new and original Design for Fabrics, of which the following is a specification, reference being had to the accompanying drawing, forming a part hereof.

10 This design relates to the ornamentation of cotton, silk, woolen, paper, celluloid, and other fabrics.

In the drawing I have shown a plan view of the design.

15 The leading feature of the design is the representation of festoons composed of holly leaves and berries with clusters of bells at

the ends of the festoons. The festoons A have their ends apparently caught and held by ribbon bows B, from which clusters of bells 20 C depend. Above the festoon A is a second festoon D of a less degree of curvature held by the bows B.

What I claim is—

The design for a fabric herein described and 25 shown.

In testimony whereof I have signed this specification in the presence of two attesting witnesses.

DAVID J. SEAMAN.

Witnesses:

L. CLARENCE BALL,
ALMEDA DICE.
